FLAT HOSIERY FRAME

Theodor Richter, Gelenau, Germany

Application April 1, 1932, Serial No. 602,408
In Germany January 21, 1932

1 Claim. (Cl. 66—82)

This invention relates to flat hosiery frames whose needle bars are moved in vertical direction by means of eccentrics of the main shaft.

As is generally known, needle bars in flat hosiery frames are, as a rule, vertically moved by the oscillating needle bar shaft to which oscillatory motion is imparted by means of roller levers and eccentrics of the main shaft. The eccentrics of the main shaft in these machines are subdivided into two halves by a vertical central line, and the rollers of the levers mentioned were hitherto positioned on the half not facing the needle bar, so that the needle bars, owing to their weight, tend to lift the rolls off from the eccentrics. This tendency is counteracted by strong springs which hold the rolls to their eccentrics. Such springs, however, of which a large number is employed in larger machines, naturally interfere with the driving element of the machines, and this has always been considered a great drawback.

According to the invention, this defect is eliminated by supporting the needle bars on their eccentrics which bring about vertical motion, the weight of the needle bars insuring perfect carrying of the rolls on their eccentrics, so that small springs for holding the rolls to their eccentrics should be employed only when the main shaft has a very high speed. These springs of course do not have to overcome the weight of the bars.

The invention will appear more clearly from the following detailed description when taken in connection with the accompanying drawing which shows in side elevation and partly in sec-

tion a device embodying the inventive idea.

In order to produce vertical motion, the needle bars 4 are, as a rule, connected with the arms 7 secured to the needle bar shaft 2. A main shaft 6 carried the eccentrics 5. The needle bars 4 are moved up and down as in tickler machines, the rolls, which are in contact with the eccentrics 5, being attached to horizontal levers 8 extending transversely to the longitudinal axis of the machine and oscillatorily disposed in the front part thereof. At their rear end these levers 8 are articulated to the vertical rods 9 which are pivoted on top to the needle bar links. The rolls are arranged approximately in the center of their length on the levers 8. In this way raising and lowering of the needle bars 4 is carried out in a very exact manner, the arms 7 being used for guiding the bars 4. It is thus possible to considerably reduce the elevations and depressions of the eccentrics 5, since the bearing points of the levers 8 are disposed at the end thereof.

I claim:—

In a flat hosiery frame, a main shaft, an eccentric carried by said shaft, a horizontal lever extending transversely to the axis of said shaft and adapted to be actuated by said eccentric, said lever being in contact with said eccentric, a needle bar, a substantially vertical rod pivotally connected with said needle bar and said lever, a needle bar shaft, and an arm connected with the needle bar shaft and with said needle bar.

THEODOR RICHTER.
